UNITED STATES PATENT OFFICE.

WINFIELD DEXTER SMITH, OF ASBURY PARK, NEW JERSEY, AND RUDOLPH J. BOURGEOIS, OF OAK PARK, ILLINOIS, ASSIGNORS TO W. D. SMITH SILVER COMPANY, OF CHICAGO, ILLINOIS, A CORPORATION OF DELAWARE.

DESIGN FOR A TEAPOT OR SIMILAR ARTICLE.

50,764.

Specification for Design.

Patented May 8, 1917.

Application filed February 27, 1917. Serial No. 151,353. Term of patent 7 years.

To all whom it may concern:

Be it known that we, WINFIELD DEXTER SMITH, a citizen of the United States, residing at Asbury Park, county of Monmouth, State of New Jersey, and RUDOLPH J. BOURGEOIS, a citizen of the United States, residing at Oak Park, county of Cook, State of Illinois, have invented a new, original, and ornamental Design for a Teapot or Similar Article, of which the following is a specification, reference being had to the accompanying drawing, forming part thereof.

The figure is a side elevation of a teapot showing our novel design.

What we claim is:—

The ornamental design for a teapot or similar article, substantially as shown.

In testimony whereof we affix our signatures.

WINFIELD DEXTER SMITH.
RUDOLPH J. BOURGEOIS.
